UNITED STATES PATENT OFFICE.

WILLIAM W. DEAN, OF CHICAGO, ILLINOIS, ASSIGNOR, BY MESNE ASSIGNMENTS, TO BENJAMIN ELECTRIC MANUFACTURING COMPANY, OF CHICAGO, ILLINOIS, A CORPORATION OF ILLINOIS.

ELECTRIC HORN.

1,209,403.

Specification of Letters Patent. Patented Dec. 19, 1916.

Application filed October 15, 1913, Serial No. 795,348. Renewed May 22, 1916. Serial No. 99,215.

To all whom it may concern:

Be it known that I, WILLIAM W. DEAN, a citizen of the United States, residing at Chicago, in the county of Cook and State of Illinois, have invented new and useful Improvements in Electric Horns, of which the following is a full, clear, concise, and exact description, reference being had to the accompanying drawing, forming a part of this 10 specification.

My invention relates to improvements in electric signal horns or alarms and has for one of its objects the production of a horn or signal which is simple in construction, efficient in operation and cheap to manufacture.

For the purpose of disclosing my invention, I have illustrated in the accompanying drawings certain embodiments thereof.

In said drawings—Figure 1 is a sectional view through the center of one embodiment of my invention; Fig. 2 is a rear view of the structure illustrated in Fig. 1, with the shell or casing removed; Fig. 3 is a sectional view of a modified form of horn embodying my invention; Fig. 4 is a rear elevation, with the casing removed, of the structure illustrated in Fig. 3; Fig. 5 is a sectional view through the center of still another form embodying my invention; Fig. 6 is a rear elevation, with the casing removed, of the structure illustrated in Fig. 5; and, Fig. 7 is a diagrammatic view illustrating the instrument applied to a motor-driven vehicle.

The embodiment illustrated is provided with the usual horn or resonator 10, which terminates in a flaring open or bell mouth and is secured at its inner end to the front section 11 of a casing containing the working parts of the signal. This front section is preferably stamped from sheet metal and is provided with a forwardly extending flange 12 around its circular central opening, and into this flange the inner end of the horn 10 fits, being secured in position by soldering, spinning over its inner edge, or by both.

The front section 11 of the casing has a rearwardly extending peripheral flange 13, within which is adapted to telescope the edge of the rear section 14 of the inclosing casing. This front section 11 also has formed thereon a circular seat 15 on which are firmly seated and clamped the working parts of the

instrument. On this seat is placed a ring or 55 gasket 16, which is preferably formed of cork composition or other suitable material and which is of large enough inside diameter to fit snugly in the flange 13 of the front section of the casing. A sound-producing 60 diaphragm 17, which is preferably formed of thin sheet metal, rests upon this gasket and is of such a diameter as to leave a clearance between its periphery and the interior of the flange 13 to accommodate the edge of 65 the back section 14 of the shell or casing. A second gasket or ring 18 is placed on the opposite side of this diaphragm, and this second ring is of substantially the same diameter as the diaphragm. These gaskets 70 prevent the entrance of moisture, dirt, etc., around the diaphragm and afford a suitable clamping surface for the edge of the diaphragm to permit it to suitably vibrate.

The gaskets and the diaphragm are held 75 in position by a clamping ring 19, which is formed of soft iron or some other suitable magnetic material and is secured in clamping position by suitable screws 20 which pass through apertures in the front section 11 of 80 the casing and are threaded into the ring 19. This ring has integrally formed therewith a pair of pole pieces or cores 21 which project inwardly from the ring toward the center of the diaphragm. These pole pieces, 85 as shown, are bent upwardly at the point 22 so that they will lie in a plane parallel with, but above, the plane of the clamping ring 19. Surrounding each of these pole pieces is an energizing winding 23, which consists 90 of wire of the proper size and kind, wound in the proper form on fiber bushings or core pieces, whereby the two windings may be slipped over the pole pieces formed as above described. Two of the terminals of the mag- 95 net coils are connected together by twisting or in any other desired manner, as at 24, and one of the terminals of one of the magnets is connected with a binding screw plate 25 by the screw 26. This plate is mounted 100 upon the clamping ring 19 and is secured in position by the screws 26 and 27, suitable insulating bushings 28 being provided for properly insulating the screws and the plate from the clamping ring. The plate 25 also 105 carries upon a suitable projection thereon a binding screw, to which one of the leading-in conductors may be attached. The arma-

ture for the magnet formed by the pole pieces 21 and windings 23 overlaps that portion of the pole pieces which projects beyond the spools and comprises a soft iron 5 plate 29 which at its rear end is riveted to a spring or reed 30 suitably clamped, by means of the screws 31, upon a shelf 32 on the clamping ring 19. The armature 29 carries a tapper 33 which, when the armature 10 is rapidly vibrated by the magnet, rapidly strikes the diaphragm, causing the same to rapidly vibrate and emit the warning sound.

The circuit through the magnet is rapidly interrupted by means of a vibrating contact, 15 preferably consisting of a platinum point on the spring arm 34 and a stationary contact 35 mounted upon the stationary arm 36. The spring arm 34 is secured by a screw 37 upon the end 38 of a plate 39 clamped upon 20 the clamping ring 19 by suitable screws 40. This clamping plate is suitably insulated from the clamping ring 19 by suitable insulating bushings 41. The screw 37 also acts as a binding-post to which one terminal of 25 the magnet 23 is connected. The arm 36 is secured in position upon the clamping ring 19 by suitable screws 42 which pass through the arm and into the clamping ring, and this arm is insulated from the clamping ring by 30 insulating bushings 43. The arm 36 also carries a binding screw 44, to which one of the conductor wires is attached. The armature 29 carries on its upper side an insulating button 45, which maintains the contacts 35 and the contact on the spring arm 34 closed. The tendency of the spring arm, however, is to open these contacts, and when the armature 29 is attracted by its magnet, due to this tendency the contacts will be 40 opened. However, as soon as the circuit is opened the armature is released from engagement with the pole pieces of the magnet and the spring 30 returns the armature to its normal position, which again closes the 45 contacts, whereby the circuit of the magnet is rapidly interrupted, causing the magnet to rapidly vibrate its armature and the tapper 33 to rapidly strike the diaphragm.

In the modified structure illustrated in 50 Figs. 3 and 4 the pole pieces 21, instead of being arranged side by side, as in the structure illustrated in Figs. 1 and 2, are arranged diametrically opposite each other on the clamping ring 19. Also, in this structure the supporting arm 36, instead of being clamped on the ring, as shown in Fig. 1,

is integrally formed therewith, and the spring 34 is mounted upon a suitable insulating post 46 held in position by the 60 screw 47.

In Figs. 5 and 6 I have illustrated a still further modification of my invention, wherein, instead of having merely a pair of pole pieces, four pole pieces are formed. These pole pieces are formed by radially extending 65 arms 48, which, like the pole pieces 21, are integrally formed with the clamping ring 19. Around these pole pieces coils 49, similar to the coils 23, are adapted to be placed and one of the terminals of one of the coils 70 is connected by the conductor 50 with the binding-post 51 on the clamping plate 39, which clamping plate also carries a binding-post 52, to which one of the conductor wires is connected. The terminal of one of the 75 other coils is connected by a conductor 53 with the spring 34, which spring is supported on the clamping plate in the same manner as is illustrated with respect to the spring 34 in Figs. 3 and 4. Also, the supporting arm 36 80 is formed in a manner similar to the supporting arm 36 illustrated in Figs. 3 and 4.

The armature for the magnet, formed as above described, comprises a circular soft 85 iron disk 54 having a pair of laterally projecting arms 55, to which are secured a pair of reeds or springs 57. The opposite ends of these reeds or springs are connected to arms 58 inwardly projecting from and integrally formed with the clamping ring 19. 90

Having thus described my invention, what I claim as new and desire to secure by Letters Patent is:

In an electric horn, the combination with 95 a diaphragm of an electromagnet for operating said diaphragm comprising a ring having a plurality of inwardly projecting pole pieces, energizing windings surrounding said pole pieces, make and break contacts for said magnet comprising an inwardly extending stationary arm carried by said ring and supporting a stationary contact, and an inwardly extending vibratory arm carrying a contact and supported by said ring. 100

In witness whereof, I have hereunto subscribed my name in the presence of two witnesses. 105
